Primary Examiner — Mary Ann Calabrese*Assistant Examiner* — Katelin G Kloberg(74) *Attorney, Agent, or Firm* — Shen Huang(57) **CLAIM**

The ornamental design for a playpen cover, as shown and described.

DESCRIPTION

FIG. 1 is a perspective view of a playpen cover, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The shade lines in the Figures show contour and not surface ornamentation.

The broken lines depict environmental subject matter that forms no part of the claimed design.

1 Claim, 7 Drawing Sheets(56)
